MANUFACTURE OR TREATMENT OF
ARTIFICIAL MATERIALS

Henry Dreyfus, London, England

Application May 4, 1932, Serial No. 609,253
In Great Britain June 4, 1931

2 Claims. (Cl. 18—54)

This invention relates to the manufacture or treatment of textile yarns or threads, and particularly to the treatment of yarns containing continuous filaments, e. g. artificial yarns of cellulose acetate or other cellulose derivatives, such as cellulose formate, propionate, and butyrate, or cellulose ethers, such as ethyl, methyl and benzyl cellulose.

The principal object of the invention is to ensure that yarns of the above character maintain the fullest strength possible during any operations in which they are employed, including the step of manufacturing such yarns. Primarily, the invention seeks to overcome or reduce any straining of the yarn arising from any tendency of the yarn to shrink after the yarn has been wound into packages or during winding.

It has been found that when cellulose derivative yarns have been subjected to a stretching operation for the purpose of increasing their strength as described in U. S. Patent No. 1,709,470, applications S. Nos. 378,684 filed 16th July 1929, 403,140 filed 28th October 1929, 573,424 filed 6th November 1931, and S. No. 605,184 filed 13th April, 1932 corresponding to British application No. 13,373/31 filed 6th May 1931, this stretching taking place beyond the elastic limit of the yarns, there is a tendency for a portion of the extension thus imparted to be recovered more or less gradually after the stretching operation has been completed, with the result that if the yarns are maintained under tension during such contraction e. g. on a compact package, by the firmly wound adjacent layers of yarn there is the danger of the yarns being strained and weakened. Likewise, high twisting of such yarns as is employed, for example, in the production of crêpe yarns results in the yarn, either by the modified structure of the yarn resulting from the high twisting of the component filaments, or by some or all of the filaments being stretched during the twisting process, tending to contract in length on being stored, with the similar danger that the yarns may be strained if kept under undesirable tension.

In either of the cases just mentioned this tendency to contract may be appreciably increased if the yarns have been treated with water or other solvent or swelling agents for the cellulose acetate or other cellulose derivative during the treatment, even though the yarns have been dried before winding. Similarly, in the treatment of cellulose acetate or other cellulose derivative yarns with a shrinking agent, it has been found that contraction of the yarn after the treatment, whether by reason of a residuum of contracting agent remaining in the yarn or even after the agent has been removed, takes place and adversely affects the

yarn if the yarn is maintained unduly tensioned. This contraction may take place even after drying of the yarns. It also happens that even with yarn wound as the final step of the spinning operation, whether by the dry or evaporative or the wet or coagulation method or a combination of these two methods, the presence of residual solvent in the yarn produces a tendency for the yarn to contract after it has become set, because this solvent evaporates from the yarn.

The disadvantage arising in this way may, apart from weakening the yarns, result in unevenness of the yarns because of unequal contraction taking place along the length of the yarns or throughout the bulk of packages containing the yarn.

It has now been found that any deleterious result which might arise from this tendency to contract can be avoided or at any rate reduced by permitting the contraction to take place while the yarn is not under substantial tension so as to reduce any tendency towards straining of the yarn. For this purpose contraction may be allowed to take place upon the bobbin, beam, or other package on to which the yarn is wound, by slackly winding the yarn thereon, so giving it freedom to contract on the package without it being subjected to strain, since undue tension is avoided. Thus, for example, in the manufacture of cellulose derivative yarns, e. g. by the dry or evaporative method, the yarn may be drawn from the jet in the usual way by a feed roller which determines the rate of production and the denier of the yarn, and then taken to a winding apparatus which builds the yarn into a package, the linear speed of winding being slightly below the linear speed of the feed roller, though not sufficiently below for there to be any danger of yarn accumulating between the feed roller and the package. Thus a drum winding device may be employed in which the speed of the drum determines the rate of winding of the yarn on a package whose surface is pressed against the drum, and the linear speed of the drum is adjusted e. g. by means of a variable friction drive, to be slightly below that of the feed roller.

In order to take full advantage of the slack winding, cross-winding of the yarn on the package may be resorted to, so giving the package a somewhat open character.

In order to ensure that whatever contraction which tends to take place does so sufficiently early to avoid excessive tensioning of the yarn, the yarn may be wetted with water or dilute solutions of solvents or swelling agents for the cellulose derivative before the yarn reaches the winding apparatus, in such cases the yarn may also be passed over or through a drying device after wetting and prior to winding.

Apparatus for slackly winding the yarn as described above may be used otherwise than continuously with the production of yarns of artificial filaments, and yarns may be treated by similar methods, during winding on other packages than bobbins. Thus, for example, the yarns may be wound slackly continuously with stretching in a bobbin to bobbin operation or continuously with the twisting of the yarn to a high degree. Or again, where a number of yarns are stretched in the form of a warp, the beam on which they are wound after stretching can be driven at such a speed that the warp is slackly wound theron. Further, such slack winding may take place otherwise than continuously with stretching or twisting, the yarn being wound after such operation on a hank for example, and then taken from the hank and rewound slackly on to a bobbin or other package.

When the yarn is stretched before winding, shrinkage may be encouraged to some extent by wetting the yarn, and if desired drying it again prior to winding. Again, in a twisting operation the yarn may be wetted before or during twisting, or, as described in U. S. application S. No. 611,922 filed 17th May, 1932 corresponding to British application No. 16,405/31 dated 4th June 1931, between stages of twisting, and may be wound either in a wet state or after drying. Further, the yarn may be treated before, during or after twisting in the manner described in U. S. applications S. Nos. 610,702 and 610,703 filed 11th April, 1932 corresponding to British application No. 14,399/31 dated 15th May, 1931, according to which a substance is formed by chemical reaction within the thread to produce shrinkage. The treatment according to U. S. applications S. Nos. 610,702 and 610,703 corresponding to British application No. 14,399/31 may be carried out in such a way as to cause shrinkage either before or after winding has been effected.

Winding of the yarns in the manner above described may with advantage be employed in conjunction with the sizing processes described for the production of crêpe yarns of cellulose acetate or other cellulose derivatives in U. S. applications S. Nos. 491,070 filed 24th October 1930, 514,898 and 514,899 filed 10th February 1931, 530,728 filed 16th April 1931, 527,358 filed 2nd April 1931, and 535,287 filed 5th May 1931, as well as with the processes of producing crêpe yarns of cellulose acetate or other cellulose derivatives described in U. S. applications S. Nos. 523,930 and 523,931 filed 19th March 1931, 550,716 filed 14th July 1931, and 559,210 filed 25th August 1931. Such yarns may be used in the swelling process for crêpe fabrics described in U. S. application S. No. 501,461 filed 10th December 1930. The winding method according to the present invention may also be used for winding the yarn described in U. S. applications S. Nos. 573,422 filed 6th November 1931 and 574,852 filed 13th November 1931.

As has been mentioned above, slack winding of the cellulose derivative yarns can be employed after stretching of the yarns in hank form, thus enabling contraction to take place freely on the wound package. Instead, however, of winding the yarns, hanks of yarns which are subject to contraction, as, for example, after treatment with water or with a shrinking agent, may be permitted to contract in the absence of tension, or under a controlled degree of tension which regulates the shrinkage to an amount

which may be permitted. After contraction has taken place, the yarns may be wound from the hanks, without, however, it being necessary to wind them slackly. If such yarns are then twisted, the precautions above indicated should again be taken to avoid undue tensioning on the subsequent contraction taking place.

In view of the increased strength of yarn obtainable by the invention, or at any rate the prevention of any serious diminution of strength arising from contraction of the yarn, yarns produced according to the invention are of value whatever their application in the textile industry. Thus in their application to crêpe fabrics, they may be used not only when highly twisted as weft or warp or both, but with a lower twist, as for a low twist warp to be used with a high or very high twist weft. The advantage arising from the invention is particularly useful in the case of yarns of low denier, especially when highly twisted.

Though the invention has been described above particularly with reference to yarns of cellulose acetate or other cellulose derivatives, it is to be understood that it may be applied to other artificial yarns, such as the reconstituted cellulose yarns, e. g. viscose, cuprammonium, and nitrocellulose silk, or to natural yarns such as natural silk, and may be employed in conjunction with the treatment of such yarns described in the specifications mentioned above and in U. S. application S. No. 559,210 filed 25th August, 1931.

The invention will now be described in greater detail with reference to the accompanying drawing, but it is to be understood that this description is given by way of example only and is in no way limitative.

Figure 1 is a side elevation of means for collecting yarns continuously with their production, 40 in the manner according to the invention.

Figure 2 shows means for carrying out the invention in a bobbin to bobbin stretching operation.

Figure 3 shows means for applying the invention continuously with the stretching of a sheet of warp yarns.

Figure 4 shows the application of the invention during a twisting operation.

Figure 5 is a view of driving means for the 50 take-up device of Figure 4.

Figure 6 shows an apparatus for drying yarns during collection, and

Figure 7 shows a method of carrying out the invention with a hank of stretched yarn.

Referring to Figure 1, a number of filaments of cellulose acetate or other organic derivatives of cellulose in the form of a thread 10 are taken from a spinning machine 11 by means of a roller 12 round which the thread passes one or more times. After leaving the roller 12 the thread 10 passes through a stationary thread guide 13 to a traversing thread guide 14 which leads the thread on to a bobbin 15 on which it is collected. The bobbin 15 is driven by means of a drum 16 contacting with the thread with bobbin 15 and rotated with a peripheral speed slightly lower than that of the feed roller 12. The feed roller 12 determines the rate at which the filaments are produced from the spinning machine 11, and collection takes place at a slightly lower speed determined by the peripheral speed of the drum 16, so that provision is made for contraction of the thread after winding on the bobbin 15. The bobbin 15 is mounted 75

in such a manner that it can rise as the bobbin fills up, the drum 16 maintaining contact with the surface of the thread wound on the bobbin so as to keep the winding rate constant.

5 In Figure 2 the thread 10 is taken from a bobbin 19 and is passed round a roller 20, after leaving which the thread 10 passes over a wick 21 applying thereto a liquid e. g. an aqueous solution of acetone, or any other of the solvent liquids mentioned in U. S. application S. No. 378,684 filed 16th July 1929, adapted to exert a solvent or softening action on the thread. The thread then passes round a second roller 22 which is geared to run at a higher speed than that of the roller 20, so that the filaments of the thread 10 having been softened by the application of liquid from the wick 21 are stretched between the rollers 20 and 22. After leaving the roller 22 the thread 10 passes to a traversing 20 guide 14 leading it on to a bobbin 15 driven by a drum 16 as described with reference to Figure 1. The drum 16 driving the bobbin 15 by contact with the yarn is rotated with a peripheral speed somewhat lower than that of the roller 22, though not so much lower as to permit the accumulation of the thread between the roller 22 and the guide 14. In this manner the thread 10 is slackly wound on the bobbin 15 and is free to shrink after winding.

30 In Figure 3 a sheet of threads 25 is taken from a beam 26 and is passed round a set of stretching rollers 27, 28, the threads 25 passing under the roller 27 and being nipped thereon by means of small rollers 28. The threads 25 then pass in a similar manner round a second set of rollers 29, 30 rotating at a higher speed than the first set 27, 28 so that the threads 25 are stretched as a whole between the two sets of rollers. If desired a washing liquor may be applied to the threads passing round the roller 29 by means of a trough 31. After leaving the rollers 29, 30 the threads 25 are given a fairly long run before reaching a second beam 32 which is rotated at a peripheral speed somewhat lower than that of the rollers 29, 30. The threads are thus kept slack between the rollers 29, 30 and the beam 32, and are slackly wound on the beam so that contraction may take place after winding. A drying plate 33 through which steam is caused to flow by means of supply and exhaust pipes 34, 35 may be provided in order to dry off the washing liquor applied from the trough 31.

55 In Figure 4 a bobbin 37 is mounted on spindle 38 and is rapidly rotated thereon. The thread 39 is drawn from the bobbin 37 and is passed through a floating ring 40 mounted on the spindle 38 in the manner described in U. S. Patent No. 1,784,581. The thread then passes through a guide 41 in line with the spindle 38, and round a feed roller 42 to a collecting device 14, 15, 16. A high degree of twist is imparted to the thread 39 while it is being drawn from the rapidly rotating bobbin 37, and in order to allow for the contraction which is liable to take place after twisting, the bobbin 15 on to which the thread 39 is traversed by means of the guide 14 is rotated by means of the drum 16 at a speed lower than that of the roller 42. If desired the yarn 39 may be wetted while passing round the roller 42 by means of a liquid contained in a trough 43 shown in dotted lines, and the yarn may be wound on the bobbin 15 in a wet state if desired.

70 Figure 5 shows an adjustable driving mecha-

nism suitable for driving the drum 16. The drive is taken from a pulley 45 to a small friction wheel 46 driving an intermediate disc 47, which in turn drives a friction wheel 48, mounted on the driving shaft of the drum 16. The axis 49 of the disc 47 is adapted to be horizontally adjustable so that the radii at which the friction wheels 46, 48 act may be varied in order to vary the rate of driving of the drum 16. The bobbin 15 is mounted freely on a spindle 50 which rises as the bobbin fills, in the manner described with reference to Figure 1. The driving mechanism described may be applied to a single twisting and collecting device, but more conveniently is adapted to drive a series of drums 16 in order to collect the twisted thread from a series of twisting devices.

Before collecting the thread in the manner according to the invention, the thread may be submitted to an aqueous treatment and dried 20 in order to produce some degree of shrinkage before twisting. For this purpose the apparatus shown in Figure 6 is suitable, wherein the thread passing round the feed roller 51 is submitted to an aqueous bath contained in a trough 52, 25 and then passes down a tube 53 having a jacket 54 for steam, hot water or other heating medium. After leaving the tube 53 the thread is collected by means of a twisting device having thread guides 13, 14, a bobbin 15 and drum 16 30 as described above.

In Figure 7 a hank of yarn 57 which has been stretched in hank form, is mounted upon a reel 58 and is drawn therefrom by means of a feed roller 59. The thread passes from the roller 59 35 to stationary guide 13, a traversing guide 14 and bobbin 15 as described above. The drum 16 which drives the bobbin 15 is caused to rotate at a speed slightly lower than that of the feed roller 59 so that the filaments are slackly wound on 40 the bobbin 15.

In any of the cases described above, in order to augment the effect of slackly winding the yarns, collecting package supports may be used, e. g. for the bobbin 16, which have resilient surfaces, 45 as described for example in U. S. application S. No. 569,251 filed 16th October, 1931.

What I claim and desire to secure by Letters Patent is:—

1. Process of packaging set cellulose acetate 50 yarn in a condition liable to produce contraction of the yarn after the same is wound on the package which comprises applying a liquid material to the yarn to assist said contraction and winding the yarn on a package support rotated at a peripheral speed slightly lower than the delivery of the yarn to the package, so that the yarn is wound on the package in such a manner that the yarn when contracted on the package is no longer slack and any tendency to strain the yarn is reduced.

2. Process of packaging set yarn containing an organic derivative of cellulose in a condition liable to produce contraction of the yarn after the same is wound on the package which comprises applying a liquid material to the yarn to assist contraction, drying said yarn and winding the dried yarn onto a package support rotated at a peripheral speed slightly lower than the delivery of the yarn to the package, so that the yarn is wound on the package in such a manner that the yarn when contracted on the package is no longer slack and any tendency to strain the yarn is reduced.

HENRY DREYFUS.
